HANDBAG LINING

Florence Freiberg, Los Angeles, Calif.

Application May 19, 1947, Serial No. 749,027

1 Claim. (Cl. 150—28)

1

The present invention relates to handbag linings in general and particularly to an improved lining for handbags in which the multitudinous objects which normally find their way into a woman's handbag can be properly positioned and retained without distorting the shape of the bag. More specifically the invention comprises a lady's handbag which incorporates a self-supporting lining including individual slide-fastener-closed pockets in which the various feminine accessories may be positioned and positively retained against accidental displacement.

The interior of the usual lady's handbag usually comprises a dismaying conglomeration of articles of feminine equipment. These may comprise compacts, combs, powder boxes, cigarettes, billfolds, check books, keys, coin purse, address book, and numberless incidental objects varying with the individual. This accumulation is usually found in one heterogeneous pile in the bottom of the bag and when the owner desires to find a particular object it is necessary to search through the entire pile in order to find the object desired, the inherent characteristic of inanimate objects being such that the desired object is usually at the bottom.

The type of objects placed in the bag varies with the individual, sometimes being relatively light and sometimes relatively heavy. They are, usually without exception, intermingled unselectively and human experience teaches that it is necessary to search for the change purse, or the compact, or the cigarettes at a time when the resultant delay will inconvenience the planned activities of others than the owner herself. Boarding a streetcar, attempting to buy a ticket in a theatre line, or seeking to pay the cashier in a food mart, are typical examples and practically without fail results in a delaying action not only to the owner but also to those waiting in the line behind her.

With an appreciation of the inherent defects and shortcomings of the devices of the prior art, it is an object of the present invention to provide a new and improved handbag.

It is another object of the invention to provide a new and improved lining for handbags.

A further object of the invention is to provide an improved lining for ladies' handbags in which individual pockets are provided for the various feminine accessories.

A still further object of the invention is to provide a lining for ladies' handbags in which a plurality of individual closed pockets are mounted upon a self-supporting lining in order that

2

the various supported objects may be maintained in position to leave unencumbered the central portion of the bag.

These and other more specific objects will appear upon reading the following specification and claims and upon considering in connection therewith the attached drawings to which they relate.

Referring now to the drawings in which a preferred embodiment of the invention is illustrated:

Figure 1 is a view in perspective of a bag lining constructed in accordance with the present invention, certain parts being broken away;

15 Figure 2 is a partial transverse horizontal section upon the line 2—2 of Figure 1;

Figure 3 is a vertical section upon the line 3—3 of Figure 1;

Figure 4 is a side view of the lining looking in 20 the direction of the arrows upon the line 4—4 of Figure 3; and

Figure 5 is a view similar to Figure 4 illustrating the opposite side of the lining.

The lining constructed in accordance with the 25 present invention is illustrated in the drawing, being indicated generally by the reference character 11, and the bag within which it is positioned, and which may be of any preferred design and material, is indicated generally by the reference character 12. The exact shapes of the bag and the lining are not important so long as the lining is adapted to fit into the bag and to be suitably secured therein as by tacking. Usually the bag itself is relatively flexible, its primary purpose being decorative, while the lining provides the functionally operative and useful part of the bag. In accordance with the preferred embodiment of the invention illustrated the bag is generally rectangular in shape and the lining is generally the same but of lesser dimensions so that it may fit therein.

Lining 11 comprises two apposed sides or faces 13 and 14 similarly shaped and preferably movably secured together around their peripheral 45 edge upon all but one side by a gusset 16. Each side member is formed of a material which preferably has considerable natural strength as to maintain a given initial shape and configuration. As illustrated in Figures 2 and 3, each side 50 is formed of a central filler element 17 which may be of cardboard, fibre board or similar relatively strong shape-maintaining material, overlaid upon its inner and outer surfaces with fabric covering, indicated at 18 and 19.

Upon the inner faces of each of side walls 13

and 14 are positioned open-topped pockets 21 which may be formed of fabric sewed to the supporting side wall. Cooperating quick-closing slide fasteners comprising interlocking elements upon the wall and the pocket and a manually movable element, indicated generally at 22 and 23, respectively, close the top of each pocket and provide means by which the contents thereof can be positively secured in place against accidental dislocation. These pockets 21 are preferably of different sizes, some being relatively wide, as indicated by the end pocket in Figures 4 and 5, while others are narrower, as indicated by the central pocket. If preferred, one of the pockets may be unprovided with closure means and so provide a seat for a cigarette package from which cigarettes may be removed as desired. Each pocket has on its outer face a label 24 upon which are found words indicating the contents. In the illustrated form in the drawings there are individual pockets for "Compact," "Comb," "Make-up," "Cigarettes," "Billfold," "Address book," "Keys" and "Coin purse." These various objects upon being positioned within their respective pockets as indicated by the labels are retained against accidental displacement by the closing of the slide fastener.

Along the top edges of the side walls 13 and 14 cooperating slide fastener elements 27 are secured which are adapted to be engaged and released manually by the user-operated element 28. As is illustrated most clearly in Figures 1 and 3, the operation of the latter makes possible the complete sealing of the interior of the lining and so the bag's interior as defined thereby.

In the use of a bag constructed in accordance with the present invention upon desiring to find a particular article the user would move the releasing element 28 so as to disengage the cooperating fastener elements 27. Thereupon admission is gained to the interior of the bag, as defined by the side walls 13 and 14. In the event that keys are desired the release element 23 is moved so as to disengage the fastening elements 22 upon the pocket marked "Keys" and thereupon the keys can be removed. The other stored elements remain within their closed pockets. It is to be noted that the various pockets are spaced above the lower portions of the side walls 13 and 14 and, accordingly, a storage space is available

5 therebelow for incidental objects which inevitably the feminine owner will desire to carry, such as handkerchiefs. As to the large mass of usual items, however, they will be positioned within their pockets and suitably retained.

10 While the particular construction herein shown and described in detail is fully capable of attaining the objects and providing the advantages hereinbefore stated, it is to be understood that it is merely illustrative of the presently preferred embodiment of the invention and that no limitations are intended as to the details of construction or design herein shown except as defined in the appended claim.

15 I claim:

20 In a handbag or the like, a self-supporting lining comprising a pair of similar apposed semi-rigid walls connected around three sides by a gusset of flexible material to enable said walls to vary their relative angular relationship within narrow limits, a plurality of adjacent pockets of flexible material each fixedly secured around three sides to one of said walls, said pockets opening toward the sides of said walls unconnected by a gusset, certain of the openings of 25 said pockets being in alignment and relatively near the side which they face and each being provided with slide fastener closing means including in each instance a part carried by the 30 pocket and a part carried by the adjacent wall, and slide fastener closing means along the side of said walls unconnected by said gusset.

FLORENCE FREEBERG.
